(57) **CLAIM**

I claim the ornamental design for a skateboard tool, as shown and described.

DESCRIPTION

FIG. 1 illustrates an upper perspective view of a skateboard tool;

FIG. 2 illustrates a right side view thereof;

FIG. 3 illustrates a left side view thereof;

FIG. 4 illustrates a rear plan view thereof;

FIG. 5 illustrates a front plan view thereof;

FIG. 6 illustrates a top view thereof; and,

FIG. 7 illustrates a bottom view thereof.

The drawings set forth a unique design for a skateboard tool. The broken lines shown in the drawings represent portions of the skateboard tool that form no part of the claimed design.
